UNITED STATES PATENT OFFICE.

WILLIAM I. THOMAS, OF NEW YORK, N. Y., ASSIGNEE TO KINESTHETIC PROCESS CO.
INC., A CORPORATION OF NEW YORK.

BALANCED GOLF BALL.

Application filed June 14, 1921. Serial No. 477,453.

To all whom it may concern:

Be it known that I, WILLIAM I. THOMAS, a citizen of the United States, residing in New York city, in the county of New York and State of New York, have invented certain new and useful Balanced Golf Balls, of which the following is a specification.

My invention relates in general to in and outdoor game apparatus, and more particularly to golf balls.

It is desirable that a golf ball shall be composed largely of rubber or other resilient material, in order that it may be driven a maximum distance by a club, but since the rubber composing the main structure of the ball is relatively light, it is desirable and usual to introduce a certain amount of heavier material into the ball, because it has been shown by experience that a weighted ball is more efficient in play.

My invention relates to the arrangement and character of the material used to give the desired weight to the ball, and its objects are to provide a structure in a golf ball which will enable the ball to resume its full sphericity and maintain its correct center of gravity in spite of the heavy blows it receives in play; which will make the body of the ball relatively homogeneous throughout, and thus contribute to its perfect action in play; and which will render the problem of placing the center of gravity of the ball in the exact center of the ball more easily controlled in manufacture.

To secure these results I arrange the material used to give the desired weight to the ball, not only at and about the center of the ball, but distributed in a progressively diminished graduation from the center to the circumference of the ball and throughout the whole body of the ball so that the weight of the central portion of the ball is highest and the weight of the portion at the circumference is lowest. And to assist in securing these results, I employ, preferably, tungsten, preferably pulverulent, as the material used to give the desired weight, or some other material whose specific gravity is not less than 17, since I have found by experiments that the volume of the material used for weighting is not

sufficient to impair greatly the resilience of the material which incorporates it if the specific gravity of the incorporated material is not less than 17.

For the purpose of description of my invention reference may be had to the accompanying drawings, in which Fig. 1, is a view in central cross-section of one form of my golf ball, Figs. 2 and 3, are central cross-sectional views of other forms, and Figs. 4 to 8 inclusive are diagrammatic views, which drawings form part of this specification, and in which similar reference characters denote similar parts throughout the several views.

Figure 1 shows a ball in central cross sectional view embodying my invention and in which A is a centerpiece of solid material, or fluid material, containing a high percentage of tungsten; B is a layer of solid rubber impregnated with tungsten, but of less relative weight than A; C is a layer of rubber thread or tape impregnated with tungsten but of less relative weight than the layer B, and wound under tension; D is a layer of rubber thread or tape less impregnated with tungsten than C, and wound under tension, and of less relative weight than the layer C; E is a layer of rubber thread or tape less impregnated with tungsten than D, and wound under tension and of less relative weight than the layer D; and F is a cover of balata or other suitable material so impregnated with tungsten that its relative weight is less than that of the layer E.

The arrangement of the various weighted portions of the ball may be varied in order to adapt the ball to the use of different classes of players. Thus, all of the graduated layers may be of rubber thread or tape wound under the highest possible tension, in which case the ball is adapted to players capable of imparting great force to the ball; or the graduated weighted layers may be also graduated in the degree of tension with which they are wound, layer B being wound at a low degree of tension and the remaining layers being wound at a progressively increased degree of tension as they proceed toward the circumference of the ball, in

which case the ball is adapted to a player who does not employ sufficient force to deliver a blow capable of giving the necessary distortion to a ball wound at the maximum tension throughout the wound portion.

- One advantage of the ball illustrated by Fig. 1, is that it tends to preserve permanently its center of gravity and sphericity in spite of the heavy blows received in play. The effect of such blows on golf balls of the customary kind and on the ball illustrated by Fig. 1, is shown by the diagrammatic views Figs. 4, 5 and 6, in which Fig. 15 4 is a view similar to Fig. 1 and of the ball shown by Fig. 1; Fig. 5 is a view in central cross section of a customary ball in which the weighted portion consists of a relatively hard, incompressible and non-resilient center piece; and Fig. 6 is a view in central cross section of another customary ball in which the weighted portion consists of a soft, compressible and relatively non-resilient center piece.
- 25 If in Figure 5 the line ST represents the force of a blow penetrating the ball to the point of T, then the force encounters at the point S' a heavy resistant and relatively incompressible center piece, and the rubber threads of the core of the ball suffer great strain, between S and S', and may be either broken or dislocated, so that the center piece tends to penetrate the weakened strands at this point, and may even move 30 as far as the cover of the ball. As a result the internal structure of the ball is impaired and its center of gravity is displaced.
- If in Figure 6 the line UV represents the force of the same blow, the blow encounters 40 at point U' a relatively soft, compressible and non-resilient center piece, and the whole body of the ball is greatly distorted by the blow which is not checked by the yielding center piece. But the center piece, being 45 non-resilient, does not assist the resilient rubber of the core in pushing back the non-resilient cover into its original spherical position, and the ball remains more or less deformed, and consequently more or less eccentric in action when further used in play.
- If in Figure 4 the line XY represents the force of the same blow, the force encounters everywhere portions of the ball which are sufficiently yielding to prevent the breaking 55 or dislocation of the rubber strands lying between any given point and the circumference of the ball, and sufficiently resilient to assist these strands in pushing back the relatively non-resilient cover into its original spherical position, and the ball tends to 60 resume its full sphericity and to preserve its correct center of gravity after a heavy blow. And I have demonstrated by laboratory tests and with the aid of a driving machine 65 that a ball of the type of structure repre-

sented in my invention and in which the material used in the weighted portions of the ball is tungsten, will recover its sphericity and preserve its center of gravity perfectly after any blow possible to be received in play, since the force of the blow encounters at all points portions of the ball which are still highly resilient though impregnated with a heavy material, owing to the fact that the impregnating material is of a very high specific gravity, and the quantity necessary to secure the desired weight at a given point is not sufficient greatly to impair the resiliency of the rubber which incorporates it.

A further object of my invention is to secure a longer and more even flight in a golf ball. The flight of a ball is dependent on the degree of distortion effected by the blow and the rapidity with which it recovers its sphericity, and is influenced also by the character and arrangement of the particles displaced by the blow. In Figure 5, the force of the blow is transmitted at first through the resilient and relatively light outer rubber windings of the core but is abruptly met and checked by the relatively unyielding, heavy and non-resilient center piece, with the result that what may be termed the rhythm of the displacement and replacement of the distorted portions of the ball is broken and the effect is shown in a break in the rhythm of the flight of the ball. The frequently observed "ducking" and hesitation of the ball in the air is due to this cause.

In the same way, the disparity between the light and resilient outer windings of the core and the heavy soft and non-resilient material in the center piece, as shown in Figure 6 results in a break of the movement of the force UV, and a consequent break in the flight of the ball.

On the contrary, in the ball as arranged by my invention and shown in Fig. 4, there is a graduated relation between the portions of the ball affected by the blow with no sudden change in the rate of distortion, and in consequence the ball has a smooth, steady and long flight.

Another object of my invention is to provide practical assistance to the manufacturer in securing a ball in which the center of gravity is correctly placed within the limits demanded in play.

If by an error in the process of manufacture the center of gravity of the weighted portion of the ball does not correspond by a given distance with the center of the ball, the center of gravity of the whole ball is disturbed more if the mass of the weighted portion is relatively small than if it is relatively large, and in the former case the ball will show more eccentricity of action than in the latter.

This effect is clearly shown in the diagrammatic views illustrated by Figs. 7 and 8. In Fig. 7, P represents a given weight of heavy material intentionally placed entirely outside of the center of a sphere of lighter material. In Fig. 8 R represents the same weight of a material of lower specific gravity distributed over a wider area but still heavier than the material which surrounds it. And in this case an error of construction equal to that shown in Fig. 7 does not result in so great a displacement of the center of gravity of the whole sphere, because the whole body of weighted material is not outside of the center of the sphere.

Consequently, a given error in placing the center of the weighted material at the center of the ball in manufacture will result in less disturbance of the center of gravity of ball and less eccentricity of action in the ball employing the structure specified in the description of my invention, in which the weight is distributed over a wider area than a ball in which the error in placing the weighted material is the same and in which the given weight of material is concentrated in a small space about the center of the ball.

Another form of structure which may be employed in a ball utilizing my invention is one in which the desired weight is given to the ball by so impregnating the center piece, the core and the cover of the ball with tungsten or other material whose specific gravity is not less than 17 that all the component parts of the ball have the same specific gravity. Or this structure may be varied by omitting the center piece, in which case this portion of the ball becomes continuous with the core, being composed of impregnated rubber thread or tape wound on itself.

Figure 2 is a central sectional view of this form of structure, in which G shows a center piece of solid rubber impregnated with tungsten or other material of a specific gravity of not less than 17; H shows a core of rubber thread or tape wound under tension and impregnated with the same material; J shows a cover impregnated with the same material. And each of the three portions of the ball G, H and J, is so impregnated with the said heavy material, that it is of the same specific gravity as each of the other two portions.

Figure 3 is a drawing of a central cross section of a ball of the general type of structure shown in Figure 2, in which the center piece is omitted, and in which K is a series of windings of impregnated rubber thread or tape wound on itself, and L is an impregnated cover of the same specific gravity as K.

The particular form of structure represented in Figures 2 and 3 is favorable to the preservation of the sphericity of the ball in spite of the heavy blows received in play,

since the material used to give the desired weight to the ball is of a specific gravity of not less than 17, and the mass employed is so small in proportion to the mass of the ball through which it is distributed that the resilience of the rubber which incorporates it is not thereby materially diminished and the whole inner portion of the ball tends to regain its shape after distortion by a blow and to assist the cover in regaining its spherical form.

Since also the force of a blow delivered on the above ball and penetrating from the circumference toward the center encounters no inequalities of structure, the rate of distortion is uniform, and in consequence the ball has a smooth and steady flight in the air.

And a form of structure in which the material used to give the desired weight to a ball is equally distributed through the whole body of the ball, as shown in Figures 2 and 3, renders it easy in manufacture to secure a well balanced ball, and one showing no eccentricity of action in play, because the center of gravity will be in the center of the ball, provided the ball is spherical in shape.

Having thus described my invention it should be understood that there may be modifications thereof and variations therein without departing from the spirit of my invention or exceeding the scope of the appended claims.

What I claim and desire to protect by Letters Patent is:

1. A golf ball comprising a center piece of resilient material impregnated for providing weight with material the specific gravity of which is not less than seventeen, and resilient material impregnated with the same material as the center piece arranged around the center piece for maintaining the center piece in normal central position in the ball when the ball is subjected to the requirements of use.

2. A golf ball comprising a center piece of resilient material impregnated for providing weight with material the specific gravity of which is not less than seventeen, and resilient material impregnated with the same material as the center piece arranged around the center piece for maintaining the center piece in normal central position in the ball and returning the ball to sphericity when the ball is subjected to the requirements of use.

3. A golf ball comprising a cover, a center piece of resilient material impregnated for providing weight with material the specific gravity of which is not less than seventeen, and resilient material impregnated with the same material as the center piece arranged around the center piece for maintaining the center piece in normal cen-

tral position in the ball and returning the ball to sphericity when the ball is subjected to the requirements of use.

4. A golf ball comprising a center piece of resilient material impregnated for providing weight with material the specific gravity of which is not less than seventeen, a cover impregnated with the same material as the center piece, and resilient material impregnated with the same material as the center piece arranged around the center piece for maintaining the center piece in normal central position in the ball and returning the ball to sphericity when the ball is subjected to the requirements of use.

5. A golf ball comprising a center piece of resilient material impregnated with material the specific gravity of which is not less than seventeen for providing weight, a core of resilient material impregnated with the same material as the center piece surrounding the center piece and arranged relative thereto for maintaining the center piece in the center of the ball against the impact of a driving implement on the ball.

6. A golf ball comprising a center piece of resilient material impregnated with material the specific gravity of which is not less than seventeen for providing weight, a core of resilient material impregnated with the same material as the center piece surrounding the center piece and arranged relative thereto for maintaining the center piece in the center of the ball against the impact of a driving implement on the ball, and a cover for the ball.

7. A golf ball comprising a center piece of resilient material impregnated with material which does not substantially detract from the resiliency of the center piece for providing weight, a core of resilient material impregnated with the same material as the center piece surrounding the center piece and arranged relative thereto for maintaining the center piece in the center of the ball against the impact of a driving implement on the ball, and a cover for the ball.

8. A golf ball comprising a center piece of resilient material impregnated with material the specific gravity of which is not less than seventeen for providing weight and which does not substantially detract from the resiliency of the center piece a core of resilient material impregnated with the same material as the center piece surrounding the center piece and arranged relative thereto for maintaining the center piece in the center of the ball against the impact of a driving implement on the ball, and a cover for the ball.

9. A golf ball comprising a center piece of resilient material impregnated with tungsten for providing weight, a core of resilient material impregnated with tungs-

ten surrounding the center piece and arranged relative thereto for maintaining the center piece in the center of the ball against the impact of a driving implement on the ball, and a cover for the ball.

10. A golf ball comprising a center piece of resilient material impregnated with pulverulent tungsten for providing weight, a core of resilient material impregnated with pulverulent tungsten surrounding the center piece and arranged relative thereto for maintaining the center piece in the center of the ball against impact of a driving implement on the ball, and a cover for the ball.

11. A golf ball comprising a center piece of resilient material impregnated with pulverulent tungsten for providing weight, a core of resilient material impregnated with pulverulent tungsten surrounding the center piece and arranged relative thereto for maintaining the center piece in the center of the ball against impact of a driving implement on the ball, and a cover for the ball impregnated with pulverulent tungsten.

12. A golf ball comprising built up layers of resilient material, each layer being impregnated for providing weight with material the specific gravity of which is not less than seventeen.

13. A golf ball comprising a center piece, and layers of resilient material built up around the center piece, each layer being impregnated for providing weight with material the specific gravity of which is not less than seventeen.

14. A golf ball comprising a center piece of weighted resilient material, and layers of resilient material built up around the center piece, each layer being impregnated for providing weight with material the specific gravity of which is not less than seventeen.

15. A golf ball comprising a center piece of resilient material impregnated for providing weight with material the specific gravity of which is not less than seventeen, and layers of resilient material built up around the center piece, each layer being impregnated with the same material as the center piece.

16. A golf ball comprising a center piece of resilient material impregnated with material the specific gravity of which is not less than seventeen and which does not substantially detract from the resiliency of the center piece, a core of resilient material impregnated with the same material as the center piece surrounding the center piece and arranged relative thereto for maintaining the center piece in the center of the ball against impact of a driving implement on the ball, and for returning the ball to sphericity after said impact, and a cover for the ball.

17. A golf ball comprising a center piece

- of resilient material impregnated with tungsten, a core of resilient material impregnated with tungsten surrounding the center piece and arranged relative thereto for maintaining the center piece in the center of the ball against impact of a driving implement on the ball, and for returning the ball to sphericity after said impact, and a cover for the ball.
18. A golf ball comprising concentric layers of weighted resilient material, there being progressive diminution in the weight of the layers from the innermost to the outermost layer.
19. A golf ball comprising concentric layers of resilient material, each layer being impregnated for providing weight with a material the specific gravity of which is not less than seventeen, there being progressive diminution of the weight of the layers from the innermost to the outermost layer.
20. A golf ball comprising a center piece, and concentric layers of weighted resilient material around the center piece, there being progressive diminution in the weight of the layers from the innermost to the outermost layer.
21. A golf ball comprising a center piece of weighted resilient material, and concentric layers of weighted resilient material around the center piece, there being progressive diminution in weight of the layers from the innermost to the outermost layer.
22. A golf ball comprising a center piece of resilient material impregnated for providing weight with material the specific gravity of which is not less than seventeen, and concentric layers of resilient material around the center piece, each layer being impregnated with the same material as the center piece, there being progressive diminution in weight of the layers from the innermost to the outermost layer.
23. A golf ball comprising a center piece of resilient material, and a core surrounding the center piece comprising concentric layers of resilient material, said center piece and layers being impregnated with weight providing material the specific gravity of which is not less than seventeen, and there being progressive diminution in weight from the center of the ball to the circumference thereof.
24. A golf ball comprising a center piece of resilient material, and a core surrounding the center piece comprising concentric layers of resilient material, said center piece and layers being impregnated with weight providing material the specific gravity of which is not less than seventeen and which does not substantially detract from the resiliency of the center piece or layers, and there being progressive diminution of weight from the center of the ball to the circumference.
25. A golf ball comprising a center piece of resilient material, and a core surrounding the center piece comprising concentric layers of resilient material, said center piece and layers being impregnated with 70 tungsten, and there being progressive diminution of weight from the center of the ball to the circumference thereof.
26. A golf ball comprising a center piece of solid material, and a core surrounding 75 the center piece comprising concentric layers of resilient material, said center piece and layers being impregnated with tungsten, and the layers being so graduated in weight that the layer immediately surrounding the 80 center piece is lighter than the center piece and the successive layers are progressively lighter than each other, the heaviest layer being nearest the center of the ball and the lightest being at the circumference of the 85 ball.
27. A golf ball comprising a center piece containing tungsten for providing weight, a layer of solid rubber successively surrounding the center piece impregnated with 90 tungsten and of less weight than the center piece, a second layer of wound rubber thread or tape successively surrounding the first layer impregnated with tungsten and of less weight than the first layer, a third layer 95 of wound rubber thread or tape successively surrounding the second layer impregnated with tungsten and of less weight than the second layer, a fourth layer of wound rubber thread or tape successively surrounding the third layer impregnated with tungsten and of less weight than the third layer, and a cover for the ball surrounding the fourth layer and of less weight than the fourth layer.
28. A golf ball comprising a center piece containing tungsten for providing weight, a layer of solid rubber successively surrounding the center piece impregnated with 100 tungsten and of less weight than the center piece, a second layer of rubber thread or tape wound under tension successively surrounding the first layer impregnated with tungsten and of less weight than the first layer, a third layer of rubber thread or tape 105 wound under tension successively surrounding the second layer and of less weight than the second layer, a fourth layer of rubber thread or tape wound under tension successively surrounding the third layer impregnated with tungsten and of less weight than the third layer, and a cover for the ball surrounding the fourth layer impregnated with tungsten and of less weight than the fourth layer.
